UNITED STATES PATENT OFFICE.

CHARLES SCOTT-SNELL, OF RIDGWAY, WIMBLEDON, ENGLAND, ASSIGNOR OF ONE-HALF
TO SIBLEYS LIMITED, OF LONDON, ENGLAND.

APPARATUS FOR COMPRESSING GAS OR AIR.

1,270,447.

Specification of Letters Patent. Patented June 25, 1918.

Application filed February 5, 1918. Serial No. 215,529.

To all whom it may concern:

Be it known that I, CHARLES SCOTT-SNELL, a subject of the King of Great Britain and Ireland, and residing at Grosvenor House, 5 Ridgway, Wimbledon, in the county of Surrey, England, have invented certain new and useful Improvements in Apparatus for Compressing Gas or Air, of which the following is a specification.

10 This invention relates to the type of apparatus in which air or gas is compressed for use at a Bunsen burner and in which such compression is effected locally by the heat generated by combustion at said burner.

15 Applied to incandescent gas lighting such compression increases the brilliancy of the light beyond that usual with gas used at ordinary low pressure.

An apparatus of this type has hitherto 20 been operated by the waste heat of the burner by placing directly over the source of heat a cylinder containing a movable piston or displacer and by means of reciprocation produced by variations of pressure 25 in the cylinder acting upon a diaphragm connected mechanically with the displacer, the elastic fluid in the cylinder is transferred alternately to the cool and heated ends of the said cylinder, the expansion of the fluid 30 under heat causing a delivery thereof to an adjacent reservoir and the condensing of the remnant causing the replenishment of the cylinder by the partial vacuum which follows, see my British Patent No. 14086 of 35 1899.

Such an apparatus is greatly affected in 40 its efficiency by the difference in temperature between the extreme ends of the cylinder and as it contains spaces of considerable 45 cubical capacity, or of as great cubical capacity as may be necessary where a separate condenser is used, there is a loss of delivery into the reservoir by the compression of the contents of the condenser.

50 An operating cylinder as above described, when placed over the source of heat, loses efficiency through the cool end attaining a considerable degree of temperature by the heat conductivity of the material forming the cylinder and the heat imparted by the hot fluid which it condenses.

The object of this invention is to reduce or avoid these difficulties and disadvantages

and enable higher efficiencies and more reliable working to be obtained.

55 The invention consists in elastic fluid compressors of the type operated directly by heat preferably the waste heat from combustion and having one or more of the following features:

A reservoir heated from the heating zone and preferably interposed between the heating zone and the compressor, whereby the operation of the latter is rendered more certain both in starting and working combined 60 with a heating chamber of small capacity at the source of heat connected to a passageway between the interior of the cylinder and its source of air supply, whereby the air under pressure on its way to the underside of the piston or displacer is highly heated when utilized.

The apparatus also comprises means consisting of a piston controlled delivery valve 65 interposed between the reservoir and the cylinder which is mechanically operated by a device attached to the piston, in which two diaphragms of different diameters receive pressure in opposite directions, the larger 70 determining the resultant direction of motion, the effective area being the difference in the respective areas; by which means the air is allowed to pass from the reservoir to the cylinder, and provide a starting impulse when the piston or displacer is at the bottom of its stroke, and when this occurs it creates a counterflow of air to allow an overflow to the reservoir to take place. Further, an improved diaphragm or piston 75 controlled exhaust valve, which, when the piston or displacer has risen to the limit of the upward motion, allows it to descend by opening communication with the atmosphere, and consequently the escape of the heated air assembled there.

90 A further feature comprises an automatic pressure controlled valve which is interposed between the reservoir and the air supply pipe to the burner, whereby the pressure in the reservoir must rise to a pre-arranged amount above atmosphere, before delivery 95 of the air is made to the burner.

100 A modified arrangement of the apparatus consists in providing a series of pistons attached to a common rod, the latter passing 105 through division walls arranged between the

pistons, whereby the amount of air operated upon by the piston rod motion is a multiple of that operated on by a single piston of the same diameter; by means of this variation a short piston rod movement can effectively act upon a large volume of air, without increasing the diameter of the cylinder.

In a further modification a reservoir can be subdivided by an internal division so that 10 heat may be applied to one section to cause pressure therein to operate the working cylinder, while the cool air enters the second division when delivered from the working cylinder, and a check valve connection between the two divisions, admitting air flow from the second division into the first division, when required, but preventing a reverse flow, thereby allowing pressure to be quickly raised for operating the cylinder 15 mechanism and avoiding the delay which would be caused by having to heat the full contents of the whole reservoir.

When a condenser (for use where gas is compressed) separate from the cylinder and 20 having large cubical capacity is provided with means for cutting off all connection with the cylinder, when the pressure stroke of the piston or displacer is in operation, losses in the fluid are thereby avoided in delivering to the reservoir due to the compression 25 of the condenser charge.

Various forms of my apparatus are shown in the accompanying figures in which:—

Figure 1 is a section of an incandescent gas lamp supplied with compressed air in accordance with my invention.

Fig. 1^A is a detail of a part of the said lamp.

Fig. 2 is a section of a modified form 40 wherein the valves and operating device are conveniently arranged for compactness.

Fig. 2^A is a diagram illustrating another arrangement of parts used in Fig. 2.

Fig. 3 is a section of my apparatus where- 45 by short stroke of the piston is combined with large delivery from the cylinder.

Fig. 3^A is a diagram of the connections adapted for a very large cylinder capacity.

Fig. 4 is a section showing internal and 50 external condensing arrangements where, as in using gas under pressure, no discharge to atmosphere is permissible.

Fig. 4^A is a detail of a valve used with the apparatus of Fig. 4.

Referring to Fig. 1, a reservoir A and a superheater reservoir A² are placed immediately over the Bunsen burner and above this is placed a cylinder B and piston C, a hollow rod C' connecting the latter to a pair of diaphragms D' and D² which, being differential in diameter, provide any desirable effective area with long travel arising from large diameter. Pressure acts upon the under side of D' by clear passage 60 from the cylinder, and upon the upper side

of D² through the hollow rod C' at C² connecting it with the cylinder. Owing to D' being the larger diaphragm, pressure causes the piston to be lifted. An inlet check valve E admits atmosphere to the cylinder when required and a plug cock F controls the connections between the reservoir and the cylinder and the cylinder and its discharge to atmosphere. This plug cock is operated by link work G in conjunction with the piston rod and by means as, for instance, a spring or a balance weight, in a well known manner, makes its full movement suddenly. A typical means is shown in Fig. 1^A where a pin in the arm G' operates in a slot in the plug attachment G² which has two angular faces and always finishes its motion by pressure from the flat surface on the spring G³ below the faces. A diaphragm valve H subject to pressure from the reservoir, allows air to flow to the burner I through pipe H² (only when a pre-arranged force is available) by lifting the valve H'. A weighted blow-off valve H² prevents over-pressure.

On account of the weight of the piston the 90 plug in the cock F when all is cold settles with its ports in the position shown in Fig. 1.

When ignition of the burner takes place the contents of the reservoir are heated, the 95 products of combustion passing away through one or more chimneys J and when pressure in the reservoir has risen sufficiently to lift the piston it is felt in the cylinder B through pipes K and L. The movement that follows causes a passage of air through the heated zone embracing pipe L and the surplus air, beyond the highly expanded portion under the piston, finds its way to the reservoir, increasing the pressure generally. At the end of the upward stroke the plug is suddenly turned $\frac{1}{4}$ th of a revolution anti-clockwise, from the position shown in the section, by the action of the diaphragm D' 100 D² on the connecting rod G, thus shutting off the reservoir, but connecting the pipe L to atmosphere. The piston C then descends, the contents on the under side passing to atmosphere and the space above the piston receiving fresh air through the inlet valve E. At the end of the down stroke the plug valve is suddenly turned back to the first position and the cycle is repeated. The cold air previously driven into the reservoir has in the meantime been acquiring heat by commingling with air already heated and still receiving heat.

Thus what may be called an "elastic fluid boiler" is being pumped up until it reaches the pre-arranged pressure which actuates valve H and starts delivering compressed air to the burner, through the injector pipe H².

In apparatus which works by transferring air from the top of a cylinder to the bottom

- by the annular clearance around the displacer, the advantages of my system of an "elastic fluid boiler" are absent and the time allowance for heating the air to fill the space under the piston is only that occupied by a half stroke of the piston, whereas by my invention the air may be many minutes in the "boiler", before it is called upon to pass out, thus being effectually heated; further the proportion of air newly pumped into the "boiler" may be small, so that the chilling effect is minimized, while the heating effect may be unlimited as the heat receiving area may be enormous without detriment to any other function of the apparatus. On the other hand to obtain large heating surface to the cylinder itself necessitates great length and high temperature to transfer the heat in the short time available.
- 20 The high temperature at the one end makes it difficult to keep down the temperature at the other end, without great prolongation of the cylinder and displacer, which further reduces efficiency inasmuch as the annulus necessary for the passage of the air becomes of considerable cubical capacity and the compression of air therein on the expansion or upward stroke reduces the delivery to the reservoir. In my invention by discharging the heated air to the atmosphere instead of condensing it I make full use of the cylinder capacity beyond that occupied by the displacer, whereas in "condensing", the amount of fresh air dealt with per stroke is materially reduced by insufficient cooling of the hot air on account of the necessity of some differences of thermal potential between outside air, walls of condenser, and internal air being cooled.
- 40 By lining the cylinder with non-conducting composition where touched by hot air, there is but little heat creeping along metallic paths. Circulation guides inside the reservoir tend to insure thorough mixing.
- 45 Both items are shown in Fig. 1.
- In Fig. 2 is shown a section in which the pressure governing valve H will be seen on the right-hand side and the chimney on the left. The reservoir is practically as in Fig. 1. The cylinder is divided into two parts B' and B², held apart by three arms M. The piston is also divided into two parts C' and C² joined by a central rod N. Diaphragms D' and D² are used differing slightly in diameter to give a preponderating influence to lifting force and capable of providing a long stroke by the relatively large diameter.
- 60 The piston in the upper section carries the inlet valve E and the upper part of the corresponding cylinder has an outlet valve P. In place of the spring controlled plug valve shown in Fig. 1, is a pair of tappet valves also spring controlled. The upper valve F² has the function of the ports joining pipe K (in Fig. 1) to the pipe E' and the lower

valve F' has the function of the ports joining pipe L to the exhaust aperture at the top of the plug cock. The movements are spring controlled by the blade Q in the rocking lever operated by the piston rod. Pressure from either of the two pins on the rod N, acting on blade Q, is inoperative until the blade is forced against a claw in the lever G which then opens a valve against pressure, and the blade returns to normal position, thus rapidly finishing the valve travel. When the lamp is cold the position of the respective parts is as shown in the drawing and the cycle of movements can be easily followed from the description of the working of the apparatus shown in Fig. 1. Both of these tappet valves when on their seats with pressure behind them tend to stay there in spite of force exerted through the feeble spring Q, but directly this is reinforced by a claw of the lever G the force removes the valve hitherto held on its seat by air pressure, and the spring continues the direction of the valve rod until the other valve is seated.

Fig. 2^a shows how the separate pistons may be carried by a rocking lever, the mechanical advantage due to unequal arms or to difference in diameter insuring motion when pressure obtains.

In Fig. 3 is shown a series of pistons working in unison in a cylinder with bulkheads, whereby a short stroke is possible with a large delivery of air. The section shows the position of all parts when the upstroke is finished and valves set ready for the down stroke. The space above all the pistons is connected to a common pipe R, and the space below to a common pipe S. The inlet valve E has the same function as the valve E in the above described drawings and valves F' and F² function as those similarly marked in relation to Fig. 2.

By placing a valve, as marked F³, in Fig. 3, the cold air from the cylinder during the upstroke enters reservoir A at this point, at the same time a continuous supply of hot air would be leaving the reservoir at valve F², therefore producing a regular circulation in the reservoir or "elastic fluid boiler". The action of the apparatus will be easily understood without further description in view of explanations of previous figures.

In Fig. 3^a is shown the reservoir divided into two parts A and A' convenient for any large delivery of air as, for instance, provided by the apparatus shown in Fig. 3. In such a case the pumped air enters the outer or large division A' first, through valve T, but a continuous feed from this through valve U, maintains a pressure in section A of the reservoir. This division makes it unnecessary to heat the whole reservoir of air where, to prevent pulsation, its total capacity is very great. Further, where rain or

snow may fall on the reservoir and cause condensation and lower the pressure, the outer part may be unprotected and remain cold without disadvantage. Delay is also avoided in starting if the whole body of air need not be heated before an operative pressure is raised.

In Fig. 4 is shown a section of a condensing pumping apparatus, *i. e.* not discharging 10 to atmosphere, in which a displaced piston C works in a cylinder B by the pressure upon a piston diaphragm D'. The dotted cover D² joining piston to cylinder prevents leakage and may be of any flexible material 15 such as rubber, to provide unrestricted movement. The plug valve F in the position shown causes reservoir pressure to obtain in the cylinder through pipe L and the piston is lifted, delivering compressed air through the 20 valve T into the reservoir, and supplying heated air through pipe L to the bottom of the cylinder. On reaching the top of the stroke the plug valve is moved enough to close delivery from pipe K and flow of 25 heated air ceases. The momentum of the piston, however, carries it on a little, tending to lessen pressure below the piston, and increase it above it. But the recoil causes the 30 previously heated air at the bottom to pass up the annular space between piston and cylinder and through valve V, which bypasses the packing, allowing the piston to fall and transfer the hot air below it to the cooler end of the cylinder; the condensation 35 that follows causes inflow of fresh air through valve E until plug valve F is thrown back to the position drawn, which restores reservoir pressure and the cycle recommences.

40 In compressing gas, as connection with atmosphere is not admissible, the valve E must be coupled, as shown dotted in Fig. 4, to a gas supply and if a separate condenser (as shown dotted and marked W) be used 45 in place of the internal condensing circulation as above described in connection with air, a check valve X is provided at the top of the condenser and also extra ports as shown in the enlarged diagram, Fig. 4^a, below, so that when the plug valve at end of 50 piston upstroke is turned $\frac{1}{4}$ th of a revolution clockwise from the position drawn it cuts off pipe K from the reservoir. It also 55 cuts off pipe L and opens a pipe Y at the bottom of cylinder (shown dotted in Fig. 4) to the condenser W, allowing a circulation, via condenser, to the space above the piston. The valve V and its by-pass tube 60 are not in this case required. At bottom of stroke the plug valve reverts to the original 65 position and reservoir pressure again obtains. As the connection with bottom of condenser is then closed and the check valve X will not allow pressure gas to enter the condenser it becomes temporarily disconnected,

and its contents are not compressed thus avoiding any resulting loss. Small tubes Z running through the reservoir and discharging into an annulus Z' at the base of the chimneys, help to rapidly generate pressure. 70

The figures throughout illustrate single acting apparatus but they may obviously be made double acting, by changes obvious to any skilled engineer, so that description is not necessary. Although plug cocks and 75 tappet valves are described other types, such as slide valves, for instance, may be used, and many minor modifications introduced without departing from the essential elements of the invention. 80

Having now described my invention, what I claim as new and desire to secure by Letters Patent is:—

1. An apparatus for furnishing compressed fluids to burners comprising a reservoir adapted to be heated and also adapted to receive the fluid to be compressed, a cylinder, a piston arranged in said cylinder, a passage connecting one end of the cylinder with said reservoir for conducting heated air to the cylinder to move said piston in one direction, a second passage connecting the other end of the cylinder to the reservoir for conducting fluid displaced by the piston in its movement under the influence 95 of the heated fluid to said reservoir, means for permitting the heated fluid to exhaust from the cylinder, means for admitting a fresh charge of fluid to the end of the cylinder connected to the second passage when 100 the heated fluid exhausts, a third passage connecting the reservoir to the burner, and a valve operated by pressure in the reservoir for controlling the fluid admitted to the third passage. 105

2. An apparatus for furnishing compressed fluid to burners comprising a fluid reservoir adapted to be heated by the burner, a cylinder containing a piston, a passage connecting the underside of the cylinder with the reservoir, a second passage connecting the upper end of the cylinder to the reservoir, means controlled by the movement of the piston for permitting the exhaust of fluid from the underside of the cylinder, means for admitting a fresh charge of fluid to the upper end of the cylinder when fluid exhausts from the underside of the cylinder, a pipe connecting the reservoir and burner, and a valve controlled by pressure in said reservoir for admitting fluid to said pipe. 115

3. An apparatus for furnishing compressed fluid to burners comprising a fluid reservoir arranged above the burner and adapted to be heated by said burner, a cylinder, a piston arranged in said cylinder, a superheater, arranged above the burner and heated thereby, a passage connecting the superheater and reservoir, a second passage 125 connecting the reservoir to the burner, and a valve controlled by pressure in the reservoir for admitting fluid to said pipe. 130

- connecting the superheater and cylinder, means for admitting a fresh charge of fluid on one side of the piston, a pipe connecting the cylinder and reservoir for conducting the fresh charge to the reservoir when the heated fluid moves said piston, and a passage connecting said reservoir to the burner.
4. An apparatus for furnishing compressed fluid to burners comprising a reservoir adapted to be heated and adapted to receive the fluid, a pipe connecting the reservoir and burner, a cylinder isolated from and communicating with said reservoir and having a piston operated by fluid heated in said reservoir, means for exhausting the heated fluid from said cylinder after it has moved said piston, and means for admitting a fresh charge of fluid to said cylinder simultaneously with the exhaust of the heated fluid from said cylinder.
5. In an apparatus for furnishing compressed fluid to burners, a reservoir for fluid adapted to be heated, a cylinder, a piston located in said cylinder and provided with a piston rod, a conduit connecting said cylinder to the reservoir for conveying heated fluid from the reservoir to the cylinder on one side of the piston, a passage connecting the cylinder on the other side of the piston, to said reservoir for conveying compressed fluid to the reservoir, means controlled by the piston rod for shutting off the heated fluid from the cylinder when said piston is at the end of its compression stroke, means for exhausting the heated fluid from the cylinder, and means for admitting a fresh charge of fluid to the cylinder when the heated fluid exhausts.
6. In an apparatus of the class described a reservoir in which the fluid is adapted to be heated, means isolated from and operated by fluid heated in the reservoir for admitting a fresh charge of fluid to the reservoir and compressing the same, and a pressure control valve for said reservoir.
7. In an apparatus of the class described, a reservoir in which the fluid is adapted to be heated, a superheater, means isolated from and operated by the fluid heated in the reservoir and superheater for admitting a fresh charge of fluid to the reservoir and compressing the same, and a pressure control valve for the reservoir.
8. In an apparatus of the class described a reservoir in which the fluid is adapted to be heated arranged above the burner, means isolated from and operated by fluid heated in the reservoir for admitting a fresh charge of fluid to the reservoir and compressing the same, and a pressure control valve for the reservoir.
9. In an apparatus for furnishing compressed fluid to burners, a reservoir in which the fluid is adapted to be heated, a cylinder isolated from said reservoir and having dividing walls separating the interior of the same into chambers, pistons in said chambers and having a common piston rod, a passage connecting the chambers with said reservoir for conveying fluid heated in the reservoir to one side of the pistons, another passage connecting the chambers with said reservoir for conveying the fluid displaced by the pistons to said reservoir, means for permitting exhaust of the heated fluid from the chambers, and means for admitting fresh fluid to the chambers simultaneously with the exhaust of the heated fluid.
10. In an apparatus of the class described, a reservoir adapted to be heated and containing fluid, means isolated from said reservoir and operated by the fluid heated in said reservoir for admitting fresh fluid to the reservoir and compressing the same in the reservoir, a passage connecting the reservoir to a fluid burner, and a pressure controlled valve for controlling the fluid passing through said passage.
11. In an apparatus of the class described, a reservoir sub-divided into two chambers, a valve controlled conduit connecting the chambers, and means isolated from said reservoir and operated by fluid heated in one chamber for admitting fresh fluid to the other chamber and for compressing fluid in said reservoir.
12. In an apparatus of the class described, a reservoir adapted to be heated, a cylinder, a piston located in said cylinder, a pipe connecting said reservoir to said cylinder for conducting fluid heated in said reservoir to said cylinder, means for admitting fresh fluid to the cylinder, a passage for conveying fluid compressed by the piston to said reservoir, a condenser, pipes connecting said condenser to both ends of the cylinder, and a valve arranged in the first named pipe and controlled by the piston, for simultaneously shutting off the passage of heated fluid to the cylinder, and permitting the heated fluid from the cylinder to exhaust into the condenser.

In testimony whereof I have signed my name to this specification.

CHARLES SCOTT-SNELL.
